BILGE PUMP

Thomas Langan, Annapolis, Md.

Application November 27, 1944, Serial No. 565,246

9 Claims. (Cl. 103—151)

This invention relates to pumps of the deformable chamber type and, more particularly, to a diaphragm pump having a valve carried by the diaphragm.

The object of the invention is to provide a bilge pump of extreme ruggedness and simplicity, the pump being manually operable with a minimum of effort but having a large output. More particularly, it is intended to provide a pump of type described having a main chamber divided into upper and lower compartments by a vertically movable diaphragm, an operating assembly for reciprocating the diaphragm, a flapper valve in the inlet to the lower compartment, a similar valve carried by the diaphragm, and a third valve in the outlet of the upper compartment so that liquid may be drawn into the pump and then exhausted through an outlet line extending to well above the level of the pump.

Another object is to provide a diaphragm pump having an external operating assembly, including handles affixed to a common shaft, the shaft being packed and extending through part of the upper compartment of the pump chamber, there being a crank and rod assembly encased entirely within the upper compartment connecting the shaft and diaphragm so that, when the handles are oscillated, the diaphragm is reciprocated in the chamber. In this assembly, it is intended to provide the pump with an upper chamber capable of having considerable pressure developed therein for exhausting water under pressure through the outlet connection and nevertheless having leak-proof seals between the inner and outer portions of the operating assembly.

These and other objects will be apparent from the following specifications and drawings, in which:

Fig. 1 is a plan view broken away to show the interior mechanism of the pump;

Fig. 2 is a vertical section; and

Fig. 3 is a front elevation.

Referring now to the drawings in which like reference numbers denote the same or similar elements, the pump includes a generally cylindrical upper body 1 and a shallow cylindrical lower body 2 having a disc-like bottom 3 rigidly affixed thereto, as by welding, soldering, brazing and the like. Welded to the bottom is an inlet connection 4 framing an inlet opening 4a through the bottom. 50

The lower and upper bodies are each provided with opposing horizontal flanges 5 and 6 welded to their respective bodies, the flanges having registering bolt holes 5a and 6a so that the flanges may be clamped towards one another by bolts 32. 55

Additional bolt openings 5b are provided in flange 5 for mounting the pump in a suitable support. Welded to the top of the upper body is a flat top 7 having a flat edge 1a terminating at the top end of a cut-away portion in the upper body, the edge 1a of the cut-away portion being as a half moon in elevation and in plan views. Welded to the edges 1a of the top and the 1a of the upper body is a sloping top 8 formed of a flat, half round plate.

An outlet box 9 is joined to sloping top 8, the outlet box consisting of a substantially rectangular top plate 9a having its rear edge welded to the upper edge of sloping top 8, triangular side plates 15 9b having their rear edges welded to the face of top 8, and a rectangular front plate 10 welded to the front edges of top and side plates 9a and 9b and to the face of top 8. An outlet connection 11 is welded to front plate 10 so that the outlet opening communicates with the interior of the upper chamber of the pump through an annular aperture 11a in front wall 10 and through an opening 8a in sloping top 8.

The opening 8a in sloping top 8 is normally 25 closed by rubber flapper valve 12 which may be suitably weighted and/or reinforced to lie flat, with one side of the flapper valve being fastened to sloping top as by bolts 33 and similar flapper valve 12' is disposed to close inlet opening 4a and 30 so held by bolts 34 threaded through suitable bolt holes in bottom 3.

The interior of the pump is divided into upper and lower compartments by flexible diaphragm 13 formed of rubber, and the periphery of the diaphragm is tightly clamped between top and bottom flanges 6 and 7. An opening, 13a, is centrally disposed in the diaphragm and framed by lower and upper flat rings 14 and 15 which are tightly clamped towards one another on the lower ends 40 of lugs 16 in operating assembly. The lower ends, 16a, of the lugs are threadedly engaged in threaded openings in lower ring 14, and the rods pass through apparatus in ring 13 so that the rings are pressed towards one another by nuts 17 threaded on the rods. A third flapper valve 12'' having one side secured by bolts 34 to upper ring 15 covers openings 13a in diaphragm 13.

The operating assembly includes the pair of vertical lugs 16 secured to rings 14 and 15 as described above and having eyes at their upper ends for holding a transverse yoke bar 18, which extends through the eyes of the lugs and is held against axial displacement by cotter pins 20.

Yoke bar 18 is directly driven by a crank arm

19 in the form of a substantially flat, wedge shaped element provided at its narrow end with an elongated slot 18a forming a lost motion connection with yoke bar 18 which extends therethrough. The crank arm has openings 19a extending therethrough to decrease the paddle effect and has at its upper end a transverse bore 22a to receive a drive shaft 22, the crank arm and drive shaft being non-rotatably joined by torque pin 31 threadedly engaged in threaded opening 19b in the crank arm and abutting on a non-round portion of drive shaft 22.

Drive shaft 22 is rotatably mounted in a tubular fibre shaft log 21 cut away at its mid-portion to accommodate the upper end of connecting rod 19 and having its exterior tightly fitted in a horizontal rectangular slot, 1s, in upper body 1 so as to form a leak-proof connection. The bore of shaft log 21 is enlarged at its ends to receive graphite packing 23 and threaded to engage the exterior threads of bronze bushings 25 held by lock nuts 24.

At the end of shaft 22 a handle collar 26 is fitted and keyed by keys 35. A handle is bolted to a tongue 28 on each collar by bolts 29 so that as the handles are oscillated, shaft 22 is rocked to reciprocate diaphragm 13 vertically.

In operation the lower end of the pump is placed in the bilge of a boat or the vessel to be pumped out, or connected to the liquid to be pumped out by a suitable pipe or hose joined to intake connection 4. When the handles are swung downwardly diaphragm 13 is raised with its flapper valve held shut, and liquid is drawn in to the interior of the lower body. When the handles are raised, diaphragm 13 is forced downwardly so that intake flapper valve 12 is closed but the diaphragm flapper valve is open so that the liquid initially drawn into exterior of the lower body now lies above the diaphragm 13. On the next down stroke of handles, diaphragm 13 is raised so as to force out liquid from the interior of the upper compartment through the outlet flapper valve and on through outlet connection 11. It should be noted that when diaphragm 13 is driven downward, back-sucking through the outlet is prevented by the flapper valve on sloping top 38.

Although the inventive structure has been described and shown in detail, it is to be understood that the invention is not limited to the specific form shown but is intended to cover mechanical equivalents and obvious modifications within the scope of the following claims.

I claim:

1. In a bilge or the like pump, a housing enclosing a chamber, a flexible diaphragm extending across said chamber and dividing the same into lower and upper compartments, said diaphragm having its edges affixed to said housing and having an aperture therethrough, said housing having inlet and outlet apertures for said lower and upper compartments, check valves operatively controlling said apertures, and means for reciprocating said diaphragm, comprising a drive shaft extending through the upper portion of said housing with the end portions of said shaft lying externally of said chamber and an intermediate portion of said shaft lying within the chamber, bearing means on said housing supporting said shaft for oscillation, a crank arm rigidly affixed to said intermediate portion of said shaft, linkage means connecting said diaphragm and said crank arm, and means on said end portions of said shaft for oscillating said shaft.

2. The combination claimed in claim 1, and packing in said bearing means, whereby to establish a substantially leakproof connection between the interior and exterior portions of said operating means.

3. The combination claimed in claim 1, said linkage including a lost-motion connection between said crank arm and said diaphragm.

4. The combination claimed in claim 1, said linkage means comprising a pair of lugs having their lower ends rigidly secured to said diaphragm on opposite sides, respectively, of the diaphragm aperture, and lost motion connection means between the upper ends of said lugs and the free end of said crank arm.

5. The combination claimed in claim 1, said linkage means comprising a pair of lugs having eyelets in their upper ends and having their lower ends rigidly secured to said diaphragm on opposite sides, respectively, of the diaphragm aperture, the free end of said crank arm lying between said eyelets and having a slot therethrough registering with said eyelets and being elongated lengthwise of said crank arm, and a yoke bar extending through said eyelets and said slot.

6. In a bilge or the like pump, a housing enclosing a chamber and having a substantially cylindrical side wall, a substantially flat bottom wall, an inlet aperture extending through said bottom wall, a flap valve having one side thereof secured to the inner side of said bottom wall and overlying said inlet aperture, a substantially dish-shaped flexible diaphragm extending across said chamber and having the edges thereof affixed to said side wall, said diaphragm having a central aperture, a flap valve having one side thereof secured to the upper side of said diaphragm and overlying the diaphragm aperture, means for reciprocating said diaphragm axially of said chamber, a top wall affixed to said side wall and having an outlet aperture therethrough, and a flap valve having one side thereof affixed to said top wall and overlying the outlet aperture, the upper portion of said side wall being cut-away on one side thereof, said top wall comprising a first sheet of material secured to the edges of the side wall at the non cut-away portion thereof and a second sheet of material having the edges thereof respectively secured to the first sheet and to the edges of the side wall at the cut-away portion thereof whereby to constitute an inclined plate, said outlet aperture being through the inclined plate.

7. In a bilge or the like pump, a housing enclosing a chamber, a flexible diaphragm extending across said chamber and dividing the same into upper and lower compartments, said diaphragm having its edges affixed to said housing and having an aperture therethrough, said housing having an inlet aperture for the lower compartment, a check valve operatively controlling said aperture, means for reciprocating said diaphragm, said housing having a top construction comprising a substantially cylindrical side wall having the upper portion thereof cut-away at one side thereof, a first half-moon shaped disc having a curved edge and a straight edge, the curved edge being affixed to the upper edges of the non-cut-away portion of the side wall, a second half-moon shaped disc having a curved edge and a straight edge, the curved edge being affixed to the upper edges of the cut-away portion of the side wall whereby to constitute an inclined plate, the straight edges of the discs being joined, said

inclined plate having an outlet aperture therethrough forming an outlet aperture for the upper compartment, and a check valve for controlling said outlet aperture.

8. In a construction as claimed in claim 7, wherein said outlet check valve comprises a flap valve having one side thereof secured to the upper surface of said inclined plate and overlying said outlet aperture, and an outlet fitting comprising a pair of substantially parallel, triangular plates having their diagonal edges respectively joined to the face of said inclined plate on each side of said outlet aperture, a rectangular plate having opposed side edges respectively joined to the top edges of said triangular plates and the rear edge thereof joined to said inclined plate, and the top edges of said triangular plates and the rear edge thereof joined to said inclined plate, whereby to protect said flap valve.

9. In a construction as claimed in claim 7, an outlet fitting comprising a pair of substantially parallel, right-triangular plates having their diagonal edges respectively joined to the face of said inclined plate on each side of said outlet aperture, a rectangular plate having opposed side edges respectively joined to the top edges of said triangular plates and the rear edge thereof joined to said inclined plate, and a rectangular front plate having an annular aperture therethrough, the edges of said front plate being respectively secured to the front edges of said triangular, rectangular, and inclined plates, and an annular tube affixed to said front plate in registry with the aperture therethrough.

THOMAS LANGAN.
